UNITED STATES PATENT OFFICE.

ARDEN D. KIMBALL, OF MILES, IOWA.

TOBACCO-BOX.

SPECIFICATION forming part of Letters Patent No. 399,050, dated March 5, 1889.

Application filed December 3, 1888. Serial No. 292,464. (No model.)

To all whom it may concern:

Be it known that I, ARDEN D. KIMBALL, a citizen of the United States, residing at Miles, in the county of Jackson and State of Iowa, have invented certain new and useful 5 Improvements in Tobacco-Boxes; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 This invention relates to tobacco and snuff boxes.

The object of the invention is to provide means for fastening the cover on the same, which consists of a weighted lock-bolt, which 20 in one position of the box extends across the joint between the box and the cover and holds the cover fast, and which in a certain other position of the box will be withdrawn from the path of the cover by the superior 25 force of gravity and permit the said cover to be readily opened.

The improvement further consists in the novel features which will be hereinafter more fully described and claimed, and shown in 30 the annexed drawings, in which—

Figure 1 is a perspective view of a box embodying my invention; Fig. 2, a perspective view, parts being broken away, showing the cover thrown back. Fig. 3 is a detail 35 section, parts being broken away, on the line $x-x$ of Fig. 1. Fig. 4 is a view similar to Fig. 3, the box being reversed; and Fig. 5 a detail top plan view of one end of the box, the cover being removed.

40 The box A may be of any desired form and size, having a thickened portion, a , which receives the gravity locking-bolt and the pivot that connects the cover thereto. The cover B, connected at one end to the box by the pivot D, is held from turning by the pin E at the other end of the box fitting in the notch b in the other end of the cover. The opening b' in the cover, through which the pivot D extends, is curved so that when the 45 cover is turned around it will at the same

time be drawn back sufficiently far to disengage it from the pin E.

The gravity locking-bolt G is mounted on the lever g , which is weighted at the end opposite the said bolt G. The purpose of the 55 weight H is to control the position of the locking-bolt G. The lever g is pivoted midway of its ends in a recess, I, in the box, and the weight and the locking-bolt work in end enlargements, i and i' , of the said recess I. 60

The supplemental cover J is mounted at one end on the pivot D, and its other end has an extension, j , which is adapted to impinge against the pin E and limit its movement. The supplemental cover is not essential, but 65 is provided to cover the slot b' in the cover B, and as a greater security against opening the box by any one not familiar with the workings of the same.

The operation of the device is as follows: 70 The covers being closed and the box placed with the covers uppermost, the weight H will gravitate and effect a projection of the locking-bolt G, which will enter the slot b' , or otherwise engage with the said cover and 75 lock the same. To open the cover, reverse the box and the weight will withdraw the locking-bolt. The covers being free, can be readily opened.

Having thus described my invention, what I 80 claim, and desire to secure by Letters Patent, is—

1. The combination, with the box, the cover pivoted at one end to one end of the box and having a notch at its other end, which is engaged by a pin on the other end of the box, the opening through which the pivot passes being extended and curved in its length, of the gravity locking-bolt adapted to enter the 85 said longitudinally-curved opening, substantially as and for the purpose described.

2. The combination, with the box and the horizontally-moving cover, of the lever pivoted midway of its ends, the weight at one end of the lever and the locking-bolt at the 95 other end of the lever, substantially as and for the purpose described.

3. The combination of the box and the covers B and J, the cover B having a notch, b , in its front end and an opening or slot, b' , 100

near its rear end, curved in its length, of the pin E for limiting the movement of the covers, the pivot D, connecting the covers with the box and passing through the said longitudinal curved opening b', and the gravity locking-bolt normally projecting into the said curved opening, substantially as described.

In testimony whereof I affix my signature in presence of two witnesses.

ARDEN D. KIMBALL
